UNITED STATES PATENT OFFICE.

FRANCISZEK MLICZEK, OF CLEVELAND, OHIO, ASSIGNOR OF ONE-HALF TO JAN BEN-BEN, OF CLEVELAND, OHIO.

DEMOUNTABLE SHADE AND CURTAIN FIXTURE.

Application filed March 9, 1922. Serial No. 542,213.

To all whom it may concern:

Be it known that I, FRANCISZEK MLICZEK, a citizen of Poland, residing at Cleveland, in the county of Cuyahoga and State of 5 Ohio, have invented certain new and useful Improvements in Demountable Shade and Curtain Fixtures, of which the following is a specification.

An object of this invention is to provide 10 a device for supporting window shades and curtain draperies that may be attached to window casings without defacing the exterior faces.

Another object is in the means provided 15 whereby the curtain and shade members may be removed without disturbing the adjustments previously made.

A further object provides a curtain roll 20 bracket that can be adjusted to engage curtain rolls of different widths.

These and other objects are attained by 25 the novel combination and arrangement of parts hereinafter described and illustrated in the accompanying drawing, forming a material part of this disclosure, and in which:—

Figure 1 is a fragmentary front elevational view of a window casing showing the fixture attached.

Figure 2 is an enlarged side elevational 30 view of the device.

Figure 3 is a partial front view of the same.

Figure 4 is a perspective view of the attaching block.

Referring to the drawing, the numeral 10 designates a window, held in a conventional casing 11, to which is secured to the outer edges, near the top, a pair of attaching 40 blocks 12 and 13, the same being made from a single sheet of relatively thin metal depressed at the center forming an oblong recess 14, its bottom being pierced at suitable points by openings 15 and 16 for engaging fixture elements.

The faces of the blocks 12 and 13 are in a level plane and their bases are provided with extending elements 17 having openings 18 receptive of screws for attaching to 45 the casing edge.

The fixture proper comprises a stamped plate 19 having a narrow extending lower tab 20, bent and shaped to engage within the lower opening 16 of the block 12.

Near the approximate center of the plate

19, is secured a stud 21, having a stem 22 slidable in the narrow portion of the opening 15 and a head 23 adapted to freely enter the larger upper portion of the same, thus providing means whereby the bracket may 60 be readily and securely attached to the casting blocks 12 and 13 or removed therefrom without the use of tools.

The curtain rod supports 24 and 25 are integral with the plate 19 and are twisted 65 upon themselves at a right angle to the plane of the plate 19, the upward extending members being curved as at 26, followed by a reversely curved terminating element 27 of lesser radius and adapted to support a horizontally disposed drapery pole 28 therein as shown in Figure 1.

Integral with the plate 19, is a bar element 29 bent at a right angle to extend inwardly adjacently across the face of the 75 window casing 11, and a plurality of depressions 30 are provided for receiving a detent finger 31 formed on the curtain roll carrier 32.

The projecting portions of the roll carrier 80 32 are of conventional type while the lower or base portions consist of angularly bent wing elements 33 and 34 formed to partially enclose and slide along the bar 29.

Due to the slight spring action of the wing 85 elements 33 and 34, the carrier detent finger 31 may be forced out of engagement with the depressions 30 and allow the carrier to be moved, thus providing means for adjusting the carriers to fit any length of curtain 90 roll within the normal range of the fixture.

It will be readily understood that the removable supporting elements, while made from the blanks having like outlines, must be subsequently formed as opposed pairs 95 adapted to engage on the right and left hand edges of casing.

As changes in construction could be made within the scope of the invention, it is intended that all matter contained in the foregoing description or shown in the accompanying drawing shall be interpreted as illustrative only and not in a limitative sense.

Having thus described my invention, what 105 I claim as new and desire to secure by Letters Patent, is:—

1. In a demountable curtain fixture, the combination with a hollow base adapted to be secured to a window casing, locking 110

means comprising a keyhole opening and a narrow rectangular slot formed thru the face of said base, a plate having an offset terminal prong suited to enter the last 5 named opening, a stud fixed in said plate to slide in the keyhole opening and having a flanged head suited to pass thru its circular portion, and an arm formed with said plate for adjustably supporting shade roll 10 brackets.

2. In a demountable curtain fixture, the combination with a hollow base adapted to be secured to a window casing, locking means comprising openings formed in the

face of the base, a plate disposed over said base, a narrow prong formed at the lower end of said plate engageable in the lower of said openings, a stud fixed in said plate engageable in the other opening, an arm extending inwardly from said plate, said arm containing a plurality of depressions, a shade fixture slideable on said arm, and a resilient detent carried by said fixture engageable selectively in any of the mentioned depressions. 15

25

In witness whereof I affix my signature.

FRANCISZEK MLICZEK.
